Henry Felmans INVENTOR

UNITED STATES PATENT OFFICE

107,718

DESIGN FOR A HANDBAG

Henri Felmann, Chicago, Ill.

Application December 8, 1937, Serial No. 73,473

Term of patent 3½ years

To all whom it may concern:

Be it known that I, Henri Felmann, a citizen of the United States of America, residing in Chicago, in the county of Cook, State of Illinois, have invented a new, original, and ornamental Design for a Handbag, of which the following is a specification, reference being had to the accompanying drawing, forming part thereof, wherein,

Figure 1 is a front view of a handbag showing my new design.

Figure 2 is an end elevational view of the handbag shown in Figure 1.

The rear portion of the handbag is identical in appearance to the front.

The characteristic feature of my design resides in the arrangement of the pleated ornamentation on either side of the bag, which ornamentation has a looped top in which double handles are attached.

I claim:

The ornamental design for a handbag, substantially as shown and described.

HENRI FELMANN.
